UNITED STATES PATENT OFFICE.

JOSEPH M. POWELL, OF ORESTES, INDIANA.

GAS, OIL, AND WATER SEPARATOR.

SPECIFICATION forming part of Letters Patent No. 703,819, dated July 1, 1902.

Application filed January 24, 1902. Serial No. 91,104. (No model.)

To all whom it may concern:

Be it known that I, JOSEPH M. POWELL, a citizen of the United States, residing at Orestes, in the county of Madison and State of Indiana, have invented new and useful Improvements in Gas, Oil, and Water Separators, of which the following is a specification.

My invention relates to gas, oil, and water separators; and the object of the same is to construct a device of this character by means of which oil and gas under pressure can be separated from water without the loss of gas by leakage. This object is accomplished by the simple and novel construction described in this specification and claimed, and illustrated in the accompanying drawing, forming a part thereof, in which the figure is a vertical longitudinal section of the separator and the well-casing.

20 The numeral 1 designates a separator-tank located adjacent to an oil-well 2, having an outer casing 3, an inner casing 4, and a well-pipe 5 extending to the bottom of the well and provided with a valve 5^a.

25 The pipe 5 is connected to the separator 1 at a point above the bottom thereof. A gas-outlet pipe 6 is also connected to the top of the tank and extends to some tank (not shown) for storing the gas or connects directly with mains. A valve 6^a is connected to this pipe.

In order to conduct the oil and water out of the separator 1, liquid-pipes 7 and 8 are connected to the bottom of the separator 1 and extend down into the well 2. The pipe 35 7 extends down between the outer casing 3 and the inner casing 4 and is provided with a valve 7^a. The pipe 8 extends down into the well 2 between the inner casing 4 and the pipe 5 to a point about on a line with the lower end 40 of the pipe 7, at which point it is turned up and extends up to the surface and terminates in an open mouth located just below the level of the bottom of the separator 1.

When in use, the valves 5^a and 6^a are open 45 and a mixture of oil, water, and gas rises through the pipe 5 and flows into the tank 1. The gas will then separate from the oil and water and rise up and pass out of the tank 1 by way of the pipe 6. If the space between 50 the outer and inner casings is filled with water, the valve 7^a in the pipe 7 is opened, which

will permit the outflow of water and oil back into the well. The escape of the gas via the pipe 7 is prevented by the water above the lower open end of the pipe. In order to form 55 a water seal to prevent all escape of gas, it is necessary to place the open mouth of the pipe 7 a distance in inches below the surface of the water in the well equal to the product of 27.6 (the height in inches of a column of water 60 exerting a pressure of one pound) and the pressure of gas in the separator given in pounds per square inch. The usual length of the pipe 7 is about ninety-two feet plus the length out of water, which corresponds to a 65 pressure of about forty pounds.

When there is no water between the casings 3 and 4, the valve 7^a is left closed and the valve 8^a opened instead. The U-shaped pipe 8 will quickly fill with water and oil up 70 to its open mouth above the surface of the ground, which water will form a seal to prevent the escape of gas. The length of the vertical column of water in each branch of the pipe 8 should be just equal to the distance 75 of the lower end of the pipe 7 below the surface of the water in the well. The oil and water will flow out of the pipe 8, when it may be caught and the oil separated from the water.

I do not wish to be limited as to details of construction, as these may be modified in many particulars without departing from the spirit of my invention.

Having thus described my invention, what 85 I claim as new, and wish to secure by Letters Patent, is—

1. The combination with a well, of a well-pipe mounted to conduct gas and oil out of said well, a separating-tank connected to said well-pipe, a gas-pipe connected to said separating-tank, a liquid-pipe connected to said separating-tank with its mouth below said gas-pipe, said liquid-pipe extending down into said well and back to the surface so that 95 the liquid retained therein will form a water seal to prevent the passage of gas therethrough, substantially as described.

2. The combination with a separating-tank, of a pipe connected to said separating-tank to conduct oil, gas and water thereinto, a gas-pipe connected to said separating-tank, and

a liquid-pipe connected to said separating-
tank below said gas-pipe, said liquid-pipe be-
ing U-shaped and arranged to hold liquid
enough to form a seal to prevent the escape of
gas from said separating-tank therethrough,
substantially as described.

In testimony whereof I have hereunto set

my hand in presence of two subscribing wit-
nesses.

JOSEPH M. POWELL.
